CLAIM

The ornamental design for an enclosure module for a portable machine, as shown and described.

DESCRIPTION

FIG. 1 is a perspective view of an enclosure module for a portable machine according to the present invention;

FIG. 2 is a top view of the enclosure module for a portable machine shown in FIG. 1, the bottom being unornamental;

FIG. 3 is a left side view of the enclosure module for a portable machine shown in FIG. 1;

FIG. 4 is a right side view of the enclosure module for a portable machine shown in FIG. 1;

FIG. 5 is a front view of the enclosure module for a portable machine shown in FIG. 1; and,

FIG. 6 is a rear view of the enclosure module for a portable machine shown in FIG. 1.
